UNITED STATES PATENT OFFICE.

JOHN SIEGEL, OF MONTREAL, CANADA.

HEEL-PROTECTOR FOR RUBBER SHOES.

SPECIFICATION forming part of Letters Patent No. 437,049, dated September 23, 1890.

Application filed May 1, 1890. Serial No. 350,398. (No model.)

To all whom it may concern:

Be it known that I, JOHN SIEGEL, of the city of Montreal, in the Province of Quebec, in the Dominion of Canada, have invented 5 certain new and useful Improvements in a Heel-Protector for Rubber Shoes; and I do hereby declare that the following is a full, clear, and exact description of the same, reference being had to the accompanying drawings, forming a part hereof.

My invention, which will be hereinafter fully set forth and claimed, relates to attachments to heels of rubber shoes or boots.

The object of my invention is an attachment 15 to the heels of rubber shoes or boots that is readily attachable and detachable, and by means of which the wear and tear of the rubber heel are prevented, and that will at the same time act as a preventive against slipping on ice and other slippery surfaces.

Figure 1 is a perspective view of a rubber shoe having my heel-protector attached. Fig. 2 is a perspective view of my protector. Fig. 3 is a side view of my protector. Fig. 4 is a 25 longitudinal section of the same; and Fig. 5 is a cross-section of the same, showing the heel of the rubber concaved by lateral compression when placing the protector in position.

My heel-protector is made of thin stiff 30 metal, preferably sheet-steel, and may be produced in dies or cast. It consists of a plate A, conforming to the shape and size of the flat portion of the heel, slightly narrower near the instep than farther rearward, provided 35 with a number of outwardly-projecting indentations a' to cause an exterior roughness, and may have perforations a'' to decrease the weight of the protector and to afford direct bearing-surfaces to the rubber. Said 40 plate is curved at the edge a adjacent to the instep to conform to the shape of the heel at the instep, so as to cause a close fit of said edge to the material of the rubber. Around said plate A, except at the instep edge, is a 45 raised rim or margin B, formed integrally with said plate or secured to it and conforming generally to the outline of the rim of the rubber heel, care being taken that the width across the plate A between the flanks of the 50 rim B is not greater, but rather less, than the breadth of the rubber heel at that point, so that the rubber will completely fill and be tightly squeezed between said rim. The rear b of the rim may be made higher than the

other portions, and be provided with a per- 55 foration b', adapted to engage the projection r, with which the heel of some rubbers are provided. The flanks of the rim B may be provided with an inwardly-projecting crimp or crease b'' to engage a corresponding indented line usually existing at the edge of the rubber heel-plate, or the crease may project outwardly to engage a projecting ridge on the rubber. Said flanks may also be provided with perforations b'''. Below said 60 crimp or crease the rim may be provided with inwardly-projecting indentations b⁴ to engage the edge of the rubber heel-plate.

In placing the protector on the heel of the rubber the latter is compressed laterally to 70 assume a concave form, and the protector is placed in position on it, as shown in Fig. 5. The concavity is then flattened out by pressure from the inside of the rubber, thus pressing the edges of the heel outward and tightly 75 engaging the rim of the protector.

I claim as my invention—

1. In a heel-protector, the combination of a plate A, conforming to the size and shape of the heel to be covered, and having the curved 80 instep edge a and provided with perforations a', and the rim B, having creases b'', perforations b''', and indentations b⁴, substantially as set forth.

2. In a heel-protector for rubbers, the combination of a metallic plate conforming to the size and shape of the heel to be covered, but slightly smaller and drawn in at the instep, a curved instep edge conforming to the curve of the instep, so as to fit the same 90 closely, and a rim at a right angle to said plate, extending around said plate from one end of said instep edge to the other and provided with a ridge or ridges, substantially as set forth.

3. A heel-protector consisting of a plate A, conforming to the size and shape of the heel to be covered, but slightly smaller and drawn in a little at the instep, and a continuous integral rigid rim or flange B, extending all 100 around said plate, from one corner of the instep to the other, substantially as set forth.

In testimony whereof I have signed in the presence of the undersigned witnesses.

J. SIEGEL.
